CLAIM

The ornamental design for a folding skateboard, as shown and described.

DESCRIPTION

FIG. 1 is a top perspective view of the folding skateboard in an extended position;

FIG. 2 is a top plan view of the folding skateboard in an extended position;

FIG. 3 is a bottom plan view of the folding skateboard in an extended position;

FIG. 4 is a left side elevational view of the folding skateboard in an extended position;

FIG. 5 is a front end elevational view of the folding skateboard in an extended position;

FIG. 6 is a rear end elevational view of the folding skateboard in an extended position;

FIG. 7 is a bottom perspective view of the folding skateboard in a folded position;

FIG. 8 is a top plan view of the folding skateboard in a folded position;

FIG. 9 is a bottom plan view of the folding skateboard in a folded position;

FIG. 10 is a right side elevational view of the folding skateboard in a folded position;

FIG. 11 is a front end elevational view of the folding skateboard in a folded position; and,

FIG. 12 is a rear end elevational view of the folding skateboard in a folded position.
